UNITED STATES PATENT OFFICE.

GEORGE F. MINNIS, OF CHICAGO, ILLINOIS.

ANCHORING DEVICE.

1,260,429.

Specification of Letters Patent. Patented Mar. 26, 1918.

Application filed July 10, 1917. Serial No. 179,679.

To all whom it may concern:

Be it known that I, GEORGE F. MINNIS, a citizen of the United States, residing at Chicago, in the county of Cook and State of Illinois, have invented certain new and useful Improvements in Anchoring Devices, of which the following is a specification.

This invention relates to improvements in anchoring devices and more particularly to 10 an anchor for attachment to a window casing.

One of the objects of my invention is to provide an anchor with a bolt taking entirely through a window casing and carrying on its outer end a pair of headed projections for engagement by a clip, such as is carried on the ends of safety ropes used by window cleaners.

Another object of my invention is to provide such an anchor which may be readily attached to buildings which have been completed without the necessity of interfering with the brick or other material used in the construction of the walls.

25 A further object is to provide an anchor which may be easily installed, is adaptable to varying conditions and has a higher factor of safety.

Still other and further objects will be 30 come apparent to those skilled in the art from a consideration of the description and drawings, wherein

Figure 1 is a perspective view of a fragment of a window casing, parts being broken 35 away, showing my improved anchor attached thereto.

Fig. 2 is a horizontal sectional view through the window casing and anchor, and;

40 Fig. 3 is a side elevation of the anchor detached from the building.

The equipment of buildings already constructed with safety devices for window washers has, in the past, received comparatively little consideration, the common method being to use lag screws taking into the wooden frame. In the case of buildings in course of construction the anchor devices usually take into the brick or other facing material and are provided with anchoring extensions held in place by the bricks and mortar.

Lag screws have, however, proved to be most dangerous, having a comparatively small factor of safety and many instances have occurred where the screws have either

broken off or pulled out resulting in the death of those dependent upon them for safety.

In the present invention I have so arranged the various parts as to eliminate in so far as possible any likelihood of breakage or pulling out and have thus anchored the safety device in a manner acceptable to building commissioners having supervision of such devices.

In the drawings I have illustrated a preferred embodiment of the invention applied to a window casing wherein the numeral 10 indicates the sash board against the ends of 70 which abut the outer and inner boards 11 and 12, respectively.

A substantially rectangular base member 13 is adapted to overlie the outer board 11 and is provided on its rounded outer surface with vertically spaced apart outwardly extending projections 14 provided with heads 15 for engagement with the clips which are attached to the ends of the safety ropes used by window washers. From the 80 rear face of the base 13 extends an elongated bolt 16 formed integral with the head and of a length sufficient to pass entirely through the outer boards 11 and 12 and sash board 10, its inner end being screw threaded, as at 85 17, for engagement with the nut 18. A plate or washer 19 is perforated to receive the bolt and has bearing against the inner board 12, a lock washer 20 underlying the nut to prevent its becoming loosened.

90 The outer end of the bolt 16 where it joins the base 13 is enlarged and given a tapered conical form, as at 21, to snugly fit the conically reamed out opening 22 formed in the outer board 11 and also to make a 95 strong enlarged connection with the base. To prevent the possibility of the base 13 turning upon the bolt as an axis I have provided at the upper and lower inner face thereof substantially opposite the heads 15 100 spurs or pointed projections 22 which take into the outer board 11 as the nut 18 is tightened.

In applying the device it is evident that the same may be attached to window casings 105 already in use by simply boring directly through the outer and inner boards 11 and 12 and sash board 10. The opening in the outer board 11 is then reamed on a taper to receive the tapered end 21 of the anchor 110 bolt. The projections 14 may be inclined inwardly somewhat, as indicated in Figs. 2

and 3, so as to be more readily engaged by the clips on the window washer's harness and as the anchor is symmetrical upon a horizontal plane it is evident that even though these parts be angled no lefts and rights are necessary.

Whereas I have illustrated and described a single embodiment of my invention it will be obvious to those skilled in the art that 10 various changes or modifications may be made therein without departing from the spirit of the invention or the scope of the appended claim.

Having described my invention, what I 15 claim is:

An anchor for engagement by a window washer's harness and for attachment to a wooden window frame having outer and inner parallel boards spaced apart by a sash

board, said anchor comprising integral 20 members consisting of an elongated base to overlie the outer board, headed projections extending outwardly from the end portions and offset to one side of the base, an elongated bolt formed integral with the base and 25 projecting rearwardly therefrom through openings formed in the outer, inner and sash boards, and a nut in screw threaded engagement with the inner end of the bolt to clamp the anchor in position, the outer 30 end of the bolt adjacent its juncture with the base being enlarged and tapered for tight engagement with the opening in the outer board.

In testimony whereof I hereunto set my 35 hand.

GEORGE F. MINNIS.
